SHAFT COUPLING

Richard F. Bergmann, Winnetka, Ill., assignor to
 Industrial Rayon Corporation, Cleveland, Ohio,
 a corporation of Delaware

Application September 10, 1942, Serial No. 457,806

2 Claims. (Cl. 64—9)

1

This invention relates to shaft couplings and provides a novel type of coupling by means of which positive driving engagement may be obtained between two shafts with the simultaneous elimination of operating difficulties resulting from any slight misalignment between the shafts.

While the shaft coupling of the present invention is readily capable of adaptation to many kindred forms of apparatus, it represents a particularly advantageous means of providing a positive driving connection between a power source and a thread-advancing thread store device. The invention is, therefore, also intended to embrace the combination of a thread-advancing thread store device and a shaft coupling.

Such thread-advancing thread store devices are used in the continuous production of synthetic fibers or threads by the viscose process. In general, the process includes the steps of extruding a spinning solution into a coagulating bath, withdrawing the coagulated thread from the bath, and thereafter subjecting it to various processing operations. In the continuous production of thread by this process, the thread is advantageously treated while temporarily stored on a plurality of thread-advancing thread store devices. The thread may be withdrawn from the bath by such a device and then passed successively over one or more additional devices on which the processing of the thread is completed. Such devices may advantageously take the form of that shown and described in Knebusch Patent No. 2,210,914, and may be supported and driven in the manner described in Torrence et al. Patent No. 2,249,798.

Because the newly coagulated thread is quite delicate, it is important that the tension to which the thread is subjected in passing from one reel to the next succeeding reel be maintained as nearly constant as possible. Variations in the tension may result in the production of threads having non-uniform dyeing characteristics.

The thread in passing over the successive reels is usually under tension and it has been found that relatively slight mechanical discrepancies in the driving engagement between the thread-advancing reel and its power source may be accentuated, apparently due to the tension in the thread, to an extent such that the reel develops what may be characterized as a "rocking motion." This results in a variation in the tension to which the thread is subjected with the result that the dyeing characteristics of the thread may be adversely affected.

The relatively slight mechanical discrepancies which appear to be the cause of this "rocking motion" arise out of unavoidable inaccuracies in machining of conventional means for effecting driving engagement between the reel shaft and the drive shaft. Such means are subject to a

2

loose or sloppy fit or tend to develop such conditions due to wear upon the interfitting parts after extended use.

In the case of the ordinary tongue and groove connection, for example, it is difficult to machine the shafts so that the elements will fit snugly together. Occasionally the tongue or the groove may be cut slightly off center with respect to the axis on the shaft on which it is formed. Moreover, wear results after such parts are assembled and operated thus accentuating misalignment therebetween. In some instances, although the driving connection may be accurately machined, the means for mounting the reel or other device operatively associated with the drive shaft may introduce conditions which effect an imperfect engagement of the driving connection. All of these factors cause the axes of the shafts to assume a non-coincident relation.

In the operation of such an imperfect tongue and groove connection, only a relatively small portion of the surface, sometimes only a corner, of the tongue is in driving contact with one of the faces of the groove at any given time. As the shafts rotate in this manner, there are two intervals in each revolution during which driving contact between the tongue and the groove shifts due to the non-coincidence of the axes of the two shafts. Thus, if one corner of the tongue is originally in driving contact with one face of the groove, the corner diagonally opposite it will thereafter contact the other face of the groove in driving relation. This action recurs at points in every revolution of the shafts which are diametrically opposite each other, thereby causing a momentary lapse in driving contact between the shafts.

Since the thread on leaving the reel is under tension, it tends to exert a rotational motion upon the reel which exceeds the angular velocity imparted to the reel by the power source. During the interval in which the aforementioned shift takes place the restraint which the constant driving motion of the drive shaft exerts in opposition to the rotational motion imparted to the reel as a result of the tension applied to the thread is momentarily removed. The tensional force applied to the thread thus imparts a sudden brief acceleration to the reel causing a sharp pull on the thread feeding onto the reel with the resultant variation in tension in a very short length of the thread.

The shaft coupling of the present invention is intended to eliminate these difficulties and is adapted to correct not only for an angular misalignment of the shafts but also for offset between them. It comprises a sleeve member having a plurality of internal axially extending

grooves adjacent each end thereof and a pair of

hub members provided with external splines adapted to engage the grooves in the sleeve member. The hub members are associated with the sleeve member in such fashion that they have an endwise movement in a substantially axial direction with respect to the sleeve member. The extent of such axial motion may be readily varied depending upon the degree of misalignment between the shafts for which correction is desired, the diameter of the shafts and other related factors.

The shaft coupling of the invention has the further advantage of being unitary in construction thereby simplifying its installation. It may, for instance, be mounted on one of the shafts so that it is readily disengageably connected to the other of the shafts, being held in place only by the supporting means for mounting the mechanism to be actuated in operating relation to the power source. In addition, the parts of the coupling of the invention are readily replaceable when they become worn.

Other advantages will become apparent to those skilled in the art as the description of the invention proceeds. In the description which follows, reference will be made to the use of one form of shaft coupling embodying the teachings of the present invention in conjunction with a typical processing reel.

Figure 1 represents a partial longitudinal cross section with parts in elevation illustrating a processing reel actuated by a power source through the medium of the shaft coupling of the instant invention. Figure 2 is a transverse cross section of the assembled coupling as it appears from a plane passed through line 2-2 in Figure 1. Figure 3 is a section similar to that of Figure 2 taken through the coupling as seen from line 3-3 in Figure 1. Figure 4 is a section through the coupling as seen from line 4-4 in Figure 1. Figure 5 illustrates the driven shaft, the drive shaft and the association of the several parts comprising the shaft coupling of the present invention in disassembled relation.

In Figure 1 of the accompanying drawings, thread-advancing reel 6 is shown as being demountably secured in cup mounting 7 of transmission 8 by means of a plurality of set screws 9 which bear against flange 10 forming part of supporting member 11 of reel 6. As previously indicated, reel 6 which is operated by shaft 12 suitably journaled in supporting member 11 is of the type shown and described in Knebusch Patent 2,210,914.

Any suitable driving means may be employed to actuate reel 6: the illustrated shaft 13 forms part of transmission 8 which represents only one of a number of suitable means. Shaft 13 is shown as being journaled in bearings 14 and is driven from gear 15 through the medium of the conventional jaw clutch mechanism 16. Gear 15 is driven by an intermeshing gear mounted upon a transverse shaft (not shown) forming part of transmission 8.

Shaft coupling 18, which connects shaft 13 of transmission 8 and shaft 12 of reel 6, comprises sleeve 19 which is provided in its internal bore 20 with a plurality of axially extending grooves 21 adjacent the ends of said sleeve. To facilitate machining, grooves 21 may extend from end to end of sleeve 19 as is desired. Disposed within bore 20 of coupling 18 is a hub member 22 having a plurality of external splines 23 which correspond in number and arrangement to grooves 21 of sleeve 19 and intermesh therewith. A greater or

lesser number of splines 23 of varying shapes may, if desired, be provided on hub member 22 depending upon the number and character of grooves 21 in bore 20 of sleeve 19 consistent with the efficient operation of coupling 18.

Hub member 22 is positioned within bore 20 of sleeve 19 and adjacent one end thereof by means of snap rings 24 which engage spaced annular grooves 25 cut into bore 20 of sleeve 19 and bear 10 against splines 23. Snap rings 24 are spaced apart a distance slightly greater than the overall width of the splined portion of hub member 22 to allow for limited endwise movement of said hub member in a substantially axial direction with respect to said sleeve 19. This freedom of movement permits hub member 22 to correct for a small amount of offset or angular misalignment of the reel shaft as will be explained hereinafter.

Hub member 22 is adapted to be demountably secured to shaft 12 of reel 6 by means of set screws 26 threaded into one or more splines 23 and key 27 which registers with keyway 28 in bore 30 of said hub member. Access to set screws 26 for adjustment thereof is provided by holes 29 which are located adjacent the position of said set screws in hub member 22: in this instance, they are illustrated as being positioned diametrically opposite to each other and extending through the wall of sleeve 19.

Disposed within bore 20 of sleeve 19 and adjacent to the end of said sleeve opposite hub member 22 is a second hub member 31. Hub member 31 is positioned between snap rings 32 which engage spaced annular grooves 33 in said bore 20 and bear against splines 34 of hub member 31 in the same manner as hub member 22. Splines 34 are substantially identical in number and disposition on hub member 31 to the corresponding splines 23 of hub member 22. Grooves 21 of sleeve 19 intermesh with splines 34 and transmit the driving force from shaft 13 of transmission 8 to splines 23 and thus serve to actuate shaft 12 of reel 6.

Hub member 31 may be mounted in any suitable fashion upon driving shaft 13 of transmission 8: in the illustrated embodiment of the invention, it is adapted to be slidably mounted upon the free end of said shaft 13. A typical mounting means comprises a pair of spaced blades 35 disposed transversely of bore 36 of hub member 31. Blades 35 are inserted in slots 37 in collar portion 38 of hub member 31 and held in place by means of a snap ring 39 set in annular groove 40 which encircles said collar portion 38. The blade construction is particularly advantageous for the reason that, in the event of wear, they may be readily replaced.

Inasmuch as coupling 18 in its preferred form is, as previously indicated, a unitary structure, it may be readily installed in apparatus with which coupling means are required. The device of the present invention is particularly adapted to apparatus of the character of that shown in Figure 1 in that it may be applied to reel 6 after which said reel may be mounted upon transmission 8 ready for operation with little, if any, resultant delay or inconvenience.

To this end coupling 18 as a unit is first mounted upon shaft 12 of reel 6 by inserting the end of said shaft in bore 38 of hub member 22 so that key 27 registers with keyway 28 after which set screws 26 are adjusted. Reel 6 with attached coupling 18 is then positioned in cup mounting 7 of transmission 8 so that tongue 41 on the end of shaft 13, when the latter is inserted

in bore 36 of hub member 31, will register with the socket formed between spaced blades 35 of said hub member. When this is accomplished, flange 10 of supporting member 11 of reel 6 will be in its proper position in cup mounting 7 and set screws 9 may be adjusted to hold the reel in place ready for operation.

In operation, shaft 13 of transmission 8 is rotated by gear 15 when jaw clutch 16 is engaged, the power being furnished by a suitable means such, for example, as a transversely extending shaft and a gear (not shown) which meshes with said gear 15. Rotation of shaft 13 is transmitted to hub member 31 through the medium of tongue 41 on said shaft and spaced blades 35 forming part of said hub member. The vertically extending sides of splines 34 of hub member 31 contact the sides of grooves 28 in sleeve 19 and impart motion to hub member 22 by virtue of the contact between the sides of splines 23 thereof with said grooves 28. Hub member 22 actuates shaft 12 thereby driving the mechanism operatively connected to said shaft, in this case, reel 6.

The spacing provided between the snap rings 24 which maintain hub member 22 in engagement with sleeve 19 and snap rings 32 which are similarly associated with hub member 31 provides both of said hub members with a limited endwise movement axially of sleeve 19. Moreover, the sides of splines 23, 34 of hub members 22 and 31, respectively, as previously indicated, are the only points of contact with grooves 28 of sleeve 19. A substantial clearance is provided not only between the points of said splines 23, 34 and the bottom of grooves 28 but also between the base of the notch between the splines on each hub member and the ridges between the grooves of sleeve 19, thus permitting a certain degree of cocking of hub members 22, 31 with respect to sleeve 19.

This freedom of movement of hub members 22 and 31 within sleeve 19 is the factor which renders the coupling of the present invention flexible without, however, affecting the positive driving relationship of the parts. Thus, the axis of rotation of either one or both of the hub members may be non-coincident with the axis of sleeve 19.

The degree of freedom required in such couplings will vary with the nature of the misalignment for which correction is to be made as well as with the sizes of the shafts to be coupled.

It will be apparent that the shaft coupling of the instant invention presents an advantageous means of correcting for inaccuracies of the character hereinbefore described which may be encountered in apparatus incorporating a drive shaft and a driven shaft. In the absence of a device such as that to which the invention relates, extreme care must be exercised not only in the manufacture but also in the assembly of the drive unit and all of the parts of the apparatus actuated thereby if the cause of such discrepancies is to be eliminated.

Many modifications in the apparatus of the invention which will occur to those familiar with the art may be made without departing from the spirit of the invention. If desirable to do so, sleeve 19 may be made up of two or more parts.

Shoulders disposed in bore 20 of sleeve 19 may supplant the innermost snap rings of each pair of rings 24 and 32. Other suitable means for attaching hub members 22 and 31 may be substituted for those shown and described.

I claim:

1. In combination, a thread-advancing store device including a rotatable shaft, a drive shaft for actuating said thread-advancing thread store device, a sleeve coupling comprising a sleeve having within it a pair of movable shafts receiving hub members for connecting said shafts, means for retaining said hub members in said sleeve, one of said hub members being adapted to receive one of said shafts and adapted to be demountably secured thereto, and the other of said hub members being provided with an axially extending bore in which are disposed at least two spaced blade members extending transversely of said bore and between which blade members an end of one of the shafts may be slidably inserted.
2. A coupling adapted to provide a positive driving engagement and correction for misalignment between two shafts comprising a fully open-ended sleeve member having axially extending grooves throughout its length, a pair of externally splined shaft receiving movable hub members retained within said sleeve member, the splines of said hub members being in mesh with the grooves of said sleeve member, each of said hub members being adapted to be inserted in one of the open ends of said sleeve member, means between said hub members for limiting the inward movement of said hub members and detachable means for maintaining the splines of said hub members in engagement in said sleeve member and permitting an endwise movement of said hub members in a substantially axial direction with respect to said sleeve member, said detachable means being adapted to be inserted in the open end of said sleeve after the hubs have been positioned, means associated with one hub member for demountably securing it to one of said shafts, and said last mentioned hub member being provided with an internal axially extending bore in which are disposed at least two spaced blade members extending transversely of said bore and between which blade members an end of one of the shafts may be slidably inserted.
